(57) **CLAIM**

The ornamental design for a grooming station, as shown and described.

DESCRIPTION

FIG. 1 is a top, front, and right side perspective view of a grooming station showing my new design;

FIG. 2 is a front elevational view thereof;

FIG. 3 is a left side elevational view thereof; and,

FIG. 4 is a top plan view thereof.

The broken-line disclosure of hooks in the views are for illustrative purposes only and forms no part of the claimed design.
